FIG. 4

UNITED STATES PATENT OFFICE

2,546,599

TOBACCO CAN HUMIDOR COVER

Edward C. Hicks, Peekskill, N. Y.

Application May 21, 1947, Serial No. 749,573

2 Claims. (Cl. 312—31.1)

1

This invention relates to tobacco humidors, and more particularly to a humidor cover for tobacco cans.

A main object of the invention is to provide a novel and improved humidor cover for tobacco cans, said cover being very simple in construction, neat in appearance and adapted to be employed with equal effectiveness either with standard commercial one pound tobacco cans or with standard commercial half pound tobacco cans.

A further object of the invention is to provide an improved humidor cover for standard commercial tobacco cans, said cover being inexpensive to manufacture, efficient in performance and sturdy in construction.

A still further object of the invention is to provide an improved humidor cover which may be alternatively employed either with a standard one pound tobacco can or with a standard half pound tobacco can, the main body portion of the cover being suitable for fabrication from plastic material or from a single sheet metal blank in a single operation and the cover being provided with spring means for effectively sealing the can on which it is used against the escape of moisture therefrom as well as providing a means for humidifying the contents thereof.

Further objects and advantages of the invention will become apparent from the following description and claims, and from the accompanying drawings, wherein:

Figure 1 is an elevational view of a standard half pound tobacco can on which is positioned a humidor cover constructed in accordance with the present invention, the cover being shown in cross-section.

Figure 2 is an elevational view, partly in cross-section, of the upper portion of a standard one pound tobacco can on which is positioned the humidor cover of Figure 1.

Figure 3 is a fragmentary top plan view of the humidor cover of Figure 1.

Figure 4 is a fragmentary cross-sectional detail view illustrating a modified form of humidor cover according to the present invention.

Referring to the drawings, 11 designates a standard half pound tobacco can such as is commonly employed as a container in which smoking tobacco is marketed to the public. The container 11 has an outer top bead 12 which serves to rigidify the top of the can. The can is ordinarily furnished with a removable flanged disc-like cover which fits tightly into an inner flange provided at the top of the can. In ac-

2

cordance with the present invention, a humidor cover 14 is employed in place of the original cover.

Cover 14 comprises a generally circular body 5 fabricated from plastic material or sheet metal, as by molding or stamping, or by any other suitable process, said body comprising a central upstanding hollow boss 15 in which is placed a mass of humidifying material such as chalk or plaster, 10 shown at 16, said mass being preferably molded in place. The cover body is substantially flat around the boss 15, as shown at 17, and is formed with an upstanding annular corrugation at 18 of substantially semi-circular cross-section. 15 Beyond the corrugation 18 the body is annularly flanged downwardly at 19 for a substantial depth, is reversely curved at 20, and is flanged upwardly at 21, terminating in an outwardly projecting annular lip or flange 24. The depending hollow 20 annular flange thus defined is preferably slightly tapered downwardly to facilitate the molding or stamping of the body, to facilitate the outward flexure of flange wall 19 when the cover is employed on a half pound can, as shown in Figure 1, 25 and to facilitate the inward flexure of flange wall 21 when the cover is employed on a one pound can, as shown in Figure 2. The spacing of the flange walls 19 and 21 is in accordance with the respective outer diameter of the bead 30 12 of a half pound can and the inside diameter of the inner cover flange 22 of a one pound can. Said depending hollow flange defined by the 35 annular flange walls 19 and 21 is also preferably of substantial depth in order to allow for reasonable manufacturing deviations of the above mentioned can diameter dimensions and to insure adequate flexural resiliency of said flange walls.

As shown in Figure 1, the inner flange wall 19 is frictionally engaged with the bead 12 and 40 is outwardly flexed thereby, thus providing a substantially vapor tight seal at the bead. When the cover is employed on a one pound can, such as shown at 23 in Figure 2, wall 21 of the hollow depending flange of the cover is frictionally engaged 45 in the inner closure flange 22 of can 23 and is inwardly flexed thereby, thus providing a substantially vapor tight seal at the closure flange. The inward flexure of outer flange wall 21 is communicated to a substantial degree by 50 the bend 20 to the inner flange wall 19, which also flexes inwardly and provides a portion of the spring reaction directed against the can closure flange 22. The upwardly projecting bend 18 provides a yielding connection between the 55 inner flange wall 19 and the flat annular portion

17, whereby said flat portion remains substantially unstressed. This prevents the central hollow boss 15 from being distorted and thereby prevents loosening or cracking of the moisture bearing hardened plastic mass 16. Said plastic mass would be ordinarily of relatively brittle material, such as chalk or plaster, as above mentioned, so that it is quite important to thus prevent distortion of the central boss 15, especially where the body of the cover is made of relatively thin plastic or of light gauge sheet material.

Where thicker plastic or heavier gauge sheet metal is employed, the inner bend 13 may be omitted, as shown in the embodiment of Figure 4. In Figure 4 the central hollow boss is shown at 15', said boss containing the moisture carrying mass 16. Extending outwardly from boss 15' is the annular flat portion 17' and depending from the outer margin thereof is the hollow tapered flange defined by inner flange wall 19', bottom bend 20', outer flange wall 21' and lip 24'. Since thicker plastic or heavier gauge sheet metal is employed than in the embodiment of Figure 1, flat portion 17' is much stiffer than the flat portion 17 of said previous embodiment and will not communicate flexural strains to boss 15'.

The hollow boss 15 of the first embodiment of the invention and the boss 15' of the second embodiment are employed as handles for manipulating the cover, as well as serving as housings for the storage of the humidifying material 16.

In either embodiment, due to the downward taper on the hollow depending outer flange of the cover, the more downward pressure there is applied to the cover the tighter is the fit.

The curves of all bends are made smooth so as to facilitate easy flow of plastic materials in molding, where the cover is made of plastic, and to prevent localized concentrations of stress, where the cover is fabricated from sheet metal.

By actual measurement, the outside diameter of the bead 12 of a standard one half pound tobacco can was found to be 4.36 inches. By a similar measurement, the inside diameter of flange 22 of a standard one pound can was found to be 4.82 inches. The mean diameter between these two values is 4.59 inches. The mean diameter of the depending hollow flange of the cover is therefore preferably close to 4.59 inches but may have any value within a range limited by the 4.36 inch outside diameter of the bead 12 of the half pound can and the 4.82 inch inside diameter of the flange 22 of the one pound can.

The preferred depth of the depending hollow flange of the cover is approximately one inch, and in a practical embodiment of the invention a depth of 0.9 inch was employed. The upward flare of the hollow annular flange is preferably such that the 4.36 inch inside diameter value occurs in the middle third of the inside flange wall 19 or 19' and the 4.82 inch outside diameter value occurs in the middle third of the outside flange wall 21 or 21'. By employing a hollow flange design as above described, substantial assurance is obtained that the flexural strains de-

veloped in the hollow flange will be distributed thereover in a uniform manner and that no strains will be transmitted to the inner flat annular portion 17 or 17' of the cover.

5 In the embodiment of Figure 4, the thickness of the main body of the cover is preferably much greater than the thickness of the walls 19' and 21' of the depending hollow flange.

While certain specific embodiments of a humidor cover for tobacco cans have been disclosed in the foregoing description, it will be understood that various modifications within the spirit of the invention may occur to those skilled in the art. Therefore it is intended that no 15 limitations be placed on the invention except as defined by the scope of the appended claims.

What is claimed is:

1. A humidor cover of the character described comprising a substantially circular body member provided at its central portion with a hollow, downwardly facing boss, a mass of molded humidifying material inside said boss, and a relatively flexible periphery provided on said body member, said periphery including a depending, 25 flexible, annular, downwardly tapered hollow rib adapted to fit either over the top bead of a standard one-half pound can or inside the inner closure flange of a standard one pound can, and an annular, flexible corrugation located inwardly 30 of said rib, the flexibility of said corrugation preventing the transmission of strains from the periphery inwardly to the hollow boss, whereby said mass of humidifying material is insulated from such strains.

35 2. A humidor cover of the character described comprising a substantially circular body member provided at its central portion with a hollow, downwardly facing boss, a mass of molded humidifying material inside said boss, a flexible, 40 annular, depending, tapered hollow rib at the periphery of said body member adapted to fit sealingly either over the top bead of a standard one-half pound can or inside the inner closure flange of a standard one pound can, and an annular, upstanding, flexible corrugation in the body member located inwardly adjacent said depending hollow rib, said flexible corrugation being adapted to absorb strains developed in the depending rib and to prevent the transmission of 50 such strains inwardly to the hollow base, whereby said mass of humidifying material is insulated from such strains.
